GLAZIER'S POINTS

Harry Thorin, Monson, Mass.

Application November 6, 1934, Serial No. 751,697

2 Claims. (Cl. 10—34)

This invention relates to improvements in glazier's points.

An object of the present invention is to provide a simple and effective manner of holding a large number of these points, at one time, by the workman, so that they may be readily and efficiently driven into the wooden window sash, or frame, without any possibility of losing, or dropping them.

At the present time, these metal points are placed on the market in a separated, or detached, condition, so that there is the disadvantage of losing many of them, while being inserted, or driven, into the sash, for retaining the pane of glass in place.

As is well known, these glazier points are usually triangular in shape, so that any one of the three (3) sharp points may be driven into the wooden sash with a suitable tool, as a chisel, in the well known manner.

Broadly stated, my improvement consists in forming a large number of these points in continuous strips, by means of suitable cutters, dies and punches, so that there is left a narrow, or small connecting portion of the strip material between the points, whereby, the glazier point at the end of the strip, may be detached, after it has been driven, or partly driven, into the sash. In practice, this continuous strip of glazier points is preferably rolled up, one over the other, into a convenient size for holding the same in one hand by the workman, while he drives the one on the extreme end of the roll with his other hand, by means of a suitable tool. After this end point has been driven into the sash, it is readily detached from the rest of the roll, by simply imparting a bending movement to the strip. It may, however, be detached, after being partially driven into the sash the required depth.

Referring to the drawing:

Fig. 1 is a plan view of a portion of a pane of glass and the sash, showing the roll, or coil, of glazier points held in one hand by a workman, and, with the other hand, in the act of driving one of the glazier points, which is located at the end of the continuous strip, into the sash.

Fig. 2 is a perspective view, showing a continuous strip of the glazier points, integrally attached together.

Fig. 3 shows one of the points removed, or detached, from the strip.

Fig. 4 illustrates a strip of metal, after being severed, to form two strips of the continuous, integrally connected, glazier points, and

Fig. 5 is a sectional view on the line 5—5 of Fig. 1.

Referring to the drawing in detail:

1 designates a portion of a wooden sash; and 2 a portion of a window pane. A continuous strip is indicated, as a whole, by the reference numeral 3, having a series of glazier points 4, integrally connected together by means of the narrow neck portion 5 of the metal strip. In Fig. 1, this continuous, metal strip 3 is shown as being coiled, or rolled, into the form, illustrated in this figure, for convenience in handling the series of glazier points, when driving them into a sash. A portion of this strip is left uncoiled, as indicated at 6, and the terminal, or end glazier point, designated by the numeral 7, is being driven into the sash, as shown. This end glazier point 7 is placed against the inner surface 8, of the sash, and the operator, by means of the chisel, or other implement, shown at 9, is in the act of striking, or imparting a blow, to the straight edge 10, of the glazier point 7; this operation being indicated by the arrow 11. After the end point 7 is driven, or partially driven into the sash, a suitable distance, the operator simply bends the portion 6 of the strip 3, whereby the narrow neck portion 5 is broken, leaving the detached glazier point firmly secured in the sash. There is, therefore, no possibility of any of the glazier points being lost, in the operation. One of the severed glazier points 30 is indicated in Fig. 3. Fig. 4 illustrates how two of the continuous metal strips 3, shown in Fig. 2, are formed, namely, by means of a suitable cutter, or die; the zig-zag cuts 12 are formed, without wasting any of the material. After these strips 35 are formed, they are coiled, or rolled, into the roll form, shown in Fig. 1.

Referring to Fig. 5, it will be seen that the point 7 is bent, or stands in a plane, at an angle to the portion 6 in the act of breaking the neck 5. 40 Also, it is bent into this position, when the point 7 is being driven into the sash, whereby the chisel 9 has plenty of room for action.

It will be seen, from this description, that I have provided a very useful and efficient means 45 for constructing and driving glazier points into a sash, for securing a pane of glass in place, and it is particularly useful for outside work, as greenhouse structures, where the sash stands in a vertical, or inclined plane, thus preventing the 50 loss of any of the glazier points, which is usually the case, when the common separated points are used. One of the advantages is that the coil, or roll, of these points, makes it easy for handling, while being driven into a sash.

What I claim is:—

1. As an article of manufacture, a continuous strip of flat glazier points integrally connected together by a neck portion, the strip being rolled 5 into a spiral coil with the points overlapping each other, into a convenient size for handling, and whereby the endmost glazier point may be unwound and driven into the sash of a window and then detached from the strip by bending the main body part of the strip at right angles to the plane 10 of the same.

2. The method of driving glazier points into a window sash which consists in first forming the points in a continuous metallic strip, leaving a neck portion between each point, then rolling a portion of the strip to form a convenient sized spiral coil for manually holding the coil, and whereby the endmost glazier point may be driven into the sash and detached therefrom after being driven in, by bending the strip, as described.
